UNITED STATES PATENT OFFICE.

CHARLES W. SOGGS AND ALVAH RITTENHOUSE, OF PHILADELPHIA, PA.

CHURN.

SPECIFICATION forming part of Letters Patent No. 251,802, dated January 3, 1882.

Application filed July 12, 1881. (No model.)

To all whom it may concern:

Be it known that we, CHARLES W. SOGGS and ALVAH RITTENHOUSE, both citizens of the United States, residing in the city and county 5 of Philadelphia, State of Pennsylvania, have invented a new and useful Improvement in Churns, which improvement is fully set forth in the following specification and accompanying drawings, in which—

10 Figure 1 is a side elevation of the churn embodying our invention. Fig. 2 is a central longitudinal vertical section of the body thereof. Fig. 3 is a bottom view of the lid. Fig. 4 is a vertical section of a detached portion in line *x* 15 *x*, Fig. 1.

Similar letters of reference indicate corresponding parts in the several figures.

This invention relates to that class of churning 20 in which a swinging body is suspended so as to tilt endwise as it swings laterally; and it consists, principally, in the construction of the 25 guard, which prevents splashing over, but admits air, and in the devices whereby said body is connected to the suspending arms, substantially as hereinafter set forth.

Referring to the drawings, A represents the body of the churn, preferably of quadrilateral form.

B represents arms, which are suspended from 30 the cross-bars C of a suitable frame, D, and are pivoted at their lower ends to the sides of the body A, it being noticed that the arms do not hang parallel, but are nearer to each other at their lower ends, or, in other words, said 35 lower ends are inside of perpendicular lines drawn from the place of pivotal connection of the upper ends of the arms.

It will be seen that when the body is set in motion it swings on the arms B, and the latter 40 swing on their pivots on the cross-bars C. Consequently, when the body completes its throw the arms on the side toward which the body is swinging depress the relative end of the body, and the other arms hold the opposite end elevated, so that the body changes from the horizontal position it occupies at the start to a diagonal position at the end of the throw in each 45 direction, the cream thus being thrown in similar directions, and being thereby violently agitated, the result of which is to bring the butter in an effective and rapid manner.

E represents a series of dashers, which are fitted perpendicularly in the body A. The dashers are constructed of slatted pieces of wood or other material, so disposed that the 55 openings *a* of one dasher alternate with those of the other dashers. By this provision the cream is caused to move in courses somewhat zigzag, thus increasing its agitation and hastening the churning operation. 60

In the lid F of the churn-body is an opening, *b*, (which may have a funnel, G,) whereby the body may be supplied with cream and receive air.

On the under side of the lid is secured a concavo-convex guard, H, formed of a disk of metal or other suitable material, the center being raised and the surrounding portion depressed, the base of the depressed or concave portion being perforated, as at *c*, and the raised or convex portion projecting toward the bottom of the inlet *b* without closing the same. 65

It will be seen that when the churn is in operation the air may readily enter the body A through the inlet *b* and openings *c* of the guard H. The contents of the body at the center thereof during splashing are directed against the guard and prevented entering the inlet, owing to the position of the convex portion of the guard adjacent to the bottom of the inlet, 75 such of the splashing cream, however, that enters the space between the guard and lid being returned to the body through the openings *c*.

In order to conveniently connect and disconnect the guard H to and from the lid, the circumference of the lid is notched, as at *d*, and the under side of the lid has secured to it in circular order lips or hooks *e*, which are so disposed that in order to apply the guard to the 80 lid the notches and hooks are caused to register, after which the guard is rotated so that its circumference between the notches comes in contact with the hooks and rests thereon, thus sustaining the guard. When the guard 85 requires removal for cleansing or repairs it is rotated until the notches and hooks register, when it may be displaced.

In order to conveniently connect and disconnect the lower ends of the arms B to and from the churn-body A, we secure to the sides of the body brackets J, one for each arm, which are 90 95 100

formed of metal depressed on the back and vertically grooved or slotted, as at *f*.

The pivots at the bottom of the arms *B* are formed with heads *g*, which enter the slots *f*, 5 and rest against the top walls of said slots and behind the same, thus allowing the utmost freedom of motion of the churn-body, and firmly sustaining the body without allowing wearing action of the arms or the pivots on said body. 10 When the body is to be separated from the arms *B* it is raised at both ends, either simultaneously or successively, and the pivots of said arms leave the brackets through the slots *f*, so that the body may be lowered or removed without interference of the arms. 15

It is evident that the connection of the arms and body may be readily accomplished by raising the body and moving the arms *B* until their lower pivots are in line or register with 20 the slots *f*. The body is then lowered, the heads of the pivots of the arms seeking their seats on the brackets, whereby the body is properly connected and suspended from the arms.

25 The body is provided with a suitable outlet for discharge of the fluid contents thereof, and may have secured to it a hook or other appliance for attachment of a rod or handle, thus enabling the working of the churn in an easy 30 manner by the operator, either sitting or standing.

The operation of the churn is furthermore facilitated by the peculiar heaving or pitching imparted to the cream as the body describes 35 its eccentric motion from horizontal to diagonal

directions. The dasher also agitates the cream uniformly throughout the body.

L designates pivoted hooks, one of which is attached to each bracket *J*, so that said hook may be swung under the headed stud that fits 40 in slot *f* of said bracket. These hooks then guard against accidental detachment of body *A* from suspending-arms *B*. They may, however, be readily turned back to allow the separation of said parts. 45

The brackets *J* are attached to the sides of body *A* at points between the middle and the ends of said body. This arrangement of attaching-points insures a greater tilting action than would be possible if the arms *B* were 50 attached to the ends of said churn-body.

Having thus described our invention, what we claim as new, and desire to secure by Letters Patent, is—

1. The concavo-convex guard *H*, bent upward in the middle, as shown, and provided with perforations *c* and peripheral notches *d*, in combination with churn-lid *F*, having inlet *b*, and hooks *e*, operating substantially as shown. 55

2. The hooks *L*, in combination with slotted brackets *J*, churn-body *A*, arms *B*, and headed pins or studs on said arms entering the slots of said brackets. 60

CHARLES W. SOGGS.
ALVAH RITTENHOUSE.
